UNITED STATES PATENT OFFICE.

JOSEPH W. PHINNEY, OF MEDFORD, MASSACHUSETTS.

DESIGN FOR A FONT OF TYPE.

SPECIFICATION forming part of Design No. 30,295, dated February 28, 1899.

Application filed August 22, 1898. Serial No. 689,253. Term of patent 7 years.

To all whom it may concern:

Be it known that I, JOSEPH W. PHINNEY, of Medford, in the county of Middlesex and State of Massachusetts, have invented and produced a new and original Design for a Font of Type, of which the following is a specification.

This design comprises capital letters and the diphthongs *Æ* and *Œ*, lower-case letters with the same diphthongs, Arabic figures, the character *&*, the dollar-mark and pounds-sterling mark, punctuation-points, the capital C with a cedilla, and the capital E with circumflex, grave, and acute accents, and also vowels of the lower-case accented, and with diereses and c with a cedilla.

The capital letters are Italic or slanting in form and are quite broad in proportion to their height, though not as broad as their height. The characteristic cross-stroke of the capital A is considerably below the middle of the letter. The lower terminal of the capital C is spear-shaped, one side of the spear-head being formed by a continuation of the curved line of the letter. The lower terminal of the capital G is quite full, and in addition to its characteristic cross-stroke has at its base a slight line projecting outward at an acute angle thereto. The capital J projects below the line, terminating in a dot connected to the stem by a line connection which broadens into the stem, the letter also having a broad coarse mark just above its middle, its top cross-stroke being scroll-shaped and terminating on its left side in a dot.

The characteristic of the letter Q starts from the exterior of the line forming the body of the letter of a width equal to the widest portion of the letter and curved downward toward the right to a point.

The dotted scroll-like characteristic of the letter J is also used in capitals A, B, D, M, N, P, R, T, and U, the lower right-hand terminal of N and R resembling also the characteristic above described of the letter Q.

The lower-case letters are characterized by a heavy stem and in the case of the round letters by the fact that the lower left-hand and upper right-hand portions of the curve are shaded, the effect being much as if the letters had been made by a very coarse pen.

The upper portion of the stem of the letters b, d, h, i, j, k, l, m, n, p, r, and u has a light line to the left of its top. The upper part or kern of the letter f is considerably narrow, so as to give the effect of a dotted kern. The letter h is somewhat wider at the top of its broad portion than at the bottom and extends below the line. The loop portion of the letter p overlaps the stem. The two lines forming the letter r are both curved, the bottom of the left-hand or broad portion of the letter entering the narrow portion above its base, and the letter w being formed of two v's, overlapping each other. The left-hand fork of the letter y is broad and has a slight line projecting downward from its upper end. The right-hand fork begins in an elongated dot and continues downward in a scroll-like manner, with a fine line shaded as it curves up below the line. The letter z has an inverted c at its bottom, extending below the line and terminating in a dot.

The numerals 1, 2, 7, and 0 are short, the other numerals extending above their upper line, the curved characteristic of the numerals 7 and 9 extending below the line and the stem of the numeral 4 extending below the line, its cross part being upon the line.

What I claim as my invention is—

The design for a font of type herein shown and described.

In testimony whereof I have hereunto set my name this 10th day of August, 1898.

JOSEPH W. PHINNEY.
